UNITED STATES PATENT OFFICE.

DAVID PETRI-PALMEDO, OF BRIDGEPORT, CONNECTICUT, ASSIGNOR TO ELECTRIC COMPOSITOR COMPANY, OF NEW YORK, N. Y., A CORPORATION OF NEW JERSEY.

TRIGGER MECHANISM FOR KEY-OPERATING MACHINES.

1,080,579.

Specification of Letters Patent.

Patented Dec. 9, 1913.

Application filed December 13, 1912. Serial No. 736,577.

To all whom it may concern:

Be it known that I, DAVID PETRI-PALMEDO, a citizen of the United States, residing at Bridgeport, in the county of Fairfield and State of Connecticut, have invented a certain new and useful Improvement in Trigger Mechanism for Key-Operating Machines, of which the following is a full, clear, and exact description.

10 In many kinds of machines, it is desirable that an operator be able by the application of slight effort to set in action a relay of power for the performance of useful work. Especially is this true in many varieties of 15 key board machines, such as matrix assembling machines, type setting machines, type-writing machines, and the like. In such machines the efficiency of the operator is in a large degree dependent upon the ease with 20 which he can operate the keys.

The object of this invention is to associate with the keys, power relay mechanism which may be set in motion by the application of slight force to the keys, and which, when 25 set in motion, will severally cause the operation of those parts, which, in key board machines, are usually operated by the keys as the direct result of the power applied thereto. With the present invention, 30 however, the keys act merely as triggers to render temporarily inoperative devices which normally restrain the operation of power driven devices capable of performing the required work when such restraining 35 devices are withdrawn.

The invention is shown in the accompanying drawings, and hereinafter described and pointed out definitely in the claims.

In said drawings, Figure 1 is a sectional 40 side elevation with the parts in normal position at rest, of the mechanism embodying this invention. Fig. 2 is a similar view of the same parts when they are in the position they occupy when the ring C has made approximately three quarters of a revolution. Fig. 3 is a front elevation partly in section of a part of a machine embodying this invention. Fig. 4 is an enlarged longitudinal section through a part of shaft B, showing 45 some of the grooves therein and associated

eccentric rings. Fig. 5 is an enlarged transverse section of shaft B showing a ring hanging in a groove therein.

Referring to the parts by letters, B represents a suitably mounted horizontal shaft 55 which extends crosswise of the machine,—which shaft is to be constantly rotated while the machine is in use. A plurality of V-shaped annular grooves b are formed in this shaft. Associated severally with these 60 grooves are trains of mechanism which are all alike and which include parts constructed and combined as follows: An eccentric ring C embraces the shaft. The ring has a cylindrical periphery; and it has also an eccentrically placed cylindrical hole c, the periphery of which is of V-shape to correspond with and fit the V-shaped groove b with which the ring is associated. The hole c is of larger diameter than the shaft and therefore these rings may be slipped endwise over the shaft and along the same to the required position. When any one of these rings is 65 permitted to hang down and rest upon the shaft, the V-shaped edge of the hole will 70 enter and nicely fit the V-shaped groove. Thereafter as the shaft turns, the ring will roll upon it because of the friction between the V surfaces. The hole of the ring being eccentric, the thick part of the ring will 75 gradually rise to the top of the shaft and will pass over and go down again, thus acting like a true eccentric. The weight of the eccentric ring is sufficient to start and maintain this action, if the angle of the V surfaces are sufficiently acute and the groove 80 sufficiently deep. The depth, however, need only be slight in any practical construction. The grip of the ring on the shaft is slight so long as no load is upon the ring. Under 85 such circumstances, however, the power required to turn the ring is slight because the ring in turning is doing no work. The grip of the ring upon the shaft, however, increases with the load applied to it; and in 90 all practical constructions for which this invention is adapted the increased grip or friction due to the load is sufficient to cause the ring to turn, and in turning to do the work required to lift the load.

The ring is normally held up and out of contact with the shaft, as shown in the drawing, by means of a shoe D which straddles a pin e carried by a lever E pivoted at e¹ 5 to a fixed frame member A. This shoe is on the rear side of the pivot of the lever. The front end of the lever projects into a notch f in the rear edge of a thin link F which is under the influence of a light spring 10 G which acts to press the link downward and rearward. The lower end of the link has a shoulder f¹ which lies above and in contact with the rear end of a pivoted key lever H. In depressing this key lever by 15 downward pressure on the key piece K secured to its front end, the link is raised, and this causes the upward rocking of the front end and a downward movement of the rear end of the lever E. This results in a 20 corresponding downward movement of the associated shoe D. When the shoe does so move down, the associated ring C will drop into the associated V groove, and will then be turned, as before stated, by said rotating 25 shaft B. As the ring turns, its thickened portion will move up and sooner or later come into contact with the load lever M, which is located above it and is pivoted at its front end to a fixed part a of the frame 30 work. Its rear end normally rests upon a fixed bar O, whereby it is held in a position such that it does not contact with the low part of the eccentric ring when the latter is in its normal position before explained,— 35 that is, the position it will occupy when the ring is resting on shoe E and is held up out of contact with the shaft. As the periphery of this ring comes in contact with this load lever M the gripping power of the ring on 40 the shaft is increased with the increased load, wherefore the ring will continue to turn. The result is that this lever M will be rocked upward by the eccentric ring and then allowed to rock back to its normal position as stated. This lever M may be associated with any suitable mechanism which it is desired to operate. In the construction 45 shown a reed N which is movable vertically in suitable guides rests at its lower end on the rear end of the load lever M. This reed may by its up and down movement operate matrix magazine escapement mechanism substantially such, for example, as is shown in the prior Patent No. 791,131. 50

55 In order that the operator may remove his finger from the key immediately after he has depressed it, to cause the stated upward movement of link F, said link is formed with the rearwardly extended lug f². 60 When the link is lifted, the spring G will move it rearward until said lug slips over a fixed bar L, whereby the link will for the time being be upheld. The link, however, is made so thick from front to rear, in that

part which is adjacent to the eccentric ring, 65 that its rear surface will, when the thick part of the ring comes adjacent to it, be engaged by said ring; wherefore the link will be pushed forward far enough to push the shoulder f² of the link off of bar L (as 70 shown in Fig. 2), whereupon said link will be moved down by its spring G. This downward movement will take place while the thick part of the ring is facing forward, but moving downward. As the link descends, lever E will be rocked and shoe D will be carried up to its normal position, where it will meet the descending thick part of the ring in such wise as to again lift the ring from the shaft. Before the ring is so 80 lifted the load lever M has come to rest with its rear end resting on bar O, so as to be out of contact with the surface of the ring. Therefore the shoe in raising the ring out of its groove has but slight friction to overcome, namely, only that friction due to the 85 weight of the ring.

To guard against the ring throwing over beyond its normal resting position, the lower edge of the bar M is provided with a shallow rearwardly projecting shoulder m, and the periphery of the ring is cut away to form a forwardly projecting shoulder o¹. These shoulders come into contact when the ring has turned as far as desired, and has 95 been lifted out of its groove.

As before stated, there are a plurality of the above described trains of mechanism. Each is associated with a groove b in shaft B. The rings C are made of such thickness, 100 that they lightly touch one another on their side faces, so as to prevent them from moving lengthwise of the shaft out of alinement with the associated grooves b in shaft B.

Having described my invention, I claim: 105

1. In trigger actuated power relay mechanism, the combination of a rotatable shaft, an eccentric ring embracing said shaft loosely, means normally holding the ring up out of contact with said shaft, means to withdraw said holding means, and a device arranged to be engaged and moved by the eccentric ring when the latter is supported and turned by said shaft.

2. In trigger actuated power relay mechanism, the combination of a rotatable shaft, an eccentric ring embracing said shaft loosely, means normally holding the ring up out of contact with said shaft, means to withdraw said holding means, and a device arranged to be engaged and moved by the eccentric when the latter is supported and turned by said shaft,—said shaft having an annular V groove and the ring having the margin of its eccentrically placed hole 115 formed of corresponding V shape.

3. In trigger actuated power relay mechanism, the combination of a rotatable shaft

having a plurality of circumferential V shaped grooves and the following mechanism associated with each groove, to wit, a circular ring having through it an eccentrically placed circular hole which is of larger diameter than the shaft, and has a V-shaped edge,—said ring being arranged in the same transverse plane as the associated groove on the shaft, means normally holding the ring up out of contact with said shaft, means to withdraw said holding means and thereby allow the ring to drop onto the shaft whereby when the shaft is turned, said eccentric ring will also be turned, and a device arranged to be engaged and moved by the eccentric ring when the latter is supported and turned by said shaft.

4. In trigger actuated power relay mechanism, the combination of a rotatable shaft, an eccentric ring embracing said shaft loosely, a vertically movable shoe arranged below said ring and adapted to lift the same out of contact with shaft, mechanism for raising and lowering said shoe, and a device arranged above the eccentric ring and adapted to be engaged and moved thereby when the latter is supported and turned by said shaft.

5. In trigger actuated power relay mechanism, the combination of a rotatable shaft, an eccentric ring embracing said shaft loosely, a vertically movable shoe arranged below said ring and adapted to lift the same out of contact with shaft, mechanism for raising and lowering said shoe, a pivoted lever engaging said shoe and adapted to raise and lower the same, mechanism for actuating the last mentioned lever, and a device arranged above the ring and adapted to be engaged and moved thereby when the latter is supported and turned by said shaft.

6. In trigger actuated power relay mechanism, the combination of a rotatable shaft, an eccentric ring embracing said shaft loosely, a vertically movable shoe arranged below said ring and adapted to lift the same out of contact with shaft, mechanism for raising and lowering said shoe, a pivoted lever engaging said shoe and adapted to raise and lower the same, mechanism for actuating the last mentioned lever, a device arranged above the ring and adapted to be engaged and moved thereby when the latter is supported and turned by said shaft, a vertically movable link for rocking lever, and a key lever for raising said link.

7. In trigger actuated power relay mechanism, the combination of a rotatable shaft, an eccentric ring embracing said shaft loosely, a vertically movable shoe arranged below said ring and adapted to lift the same out of contact with shaft, mechanism for raising and lowering said shoe, a pivoted lever engaging said shoe and adapted to

raise and lower the same, mechanism for actuating the last mentioned lever, a device arranged above the ring and adapted to be engaged and moved thereby when the latter is supported and turned by said shaft, a vertically movable link for rocking said lever, which link has a rearwardly projecting shoulder, a bar over which said shoulder may be hooked when the link is raised, a spring acting to push the link rearward, and means whereby the link will be pushed forward to disengage the shoulder from said bar when the ring has nearly completed one revolution.

8. In trigger actuated power relay mechanism, the combination of a rotatable shaft, an eccentric ring embracing said shaft loosely, a vertically movable shoe arranged below said ring and adapted to lift the same out of contact with shaft, mechanism for raising and lowering said shoe, a pivoted lever engaging said shoe and adapted to raise and lower the same, mechanism for actuating the last mentioned lever, a device arranged above the ring and adapted to be engaged and moved thereby when the latter is supported and turned by said shaft, a vertically movable link for rocking said lever, which link has a rearwardly projecting shoulder, a bar over which said shoulder may be hooked when the link is raised, a spring acting to push the link rearward, said link being extended rearwardly adjacent to the ring to such position that it will be engaged by the periphery of the eccentric ring and pushed forward so as to disengage the shoulder from said bar while the ring is being turned by said shaft.

9. In trigger actuated power relay mechanism, the combination of a rotatable shaft, an eccentric ring embracing said shaft loosely, a shoe arranged below said ring and adapted to be raised and lowered, and when raised to lift the ring out of engagement with the shaft and when lowered to allow the ring to hang upon the shaft, means for raising and lowering said shoe, a vertically movable device above the ring and arranged to be engaged and lifted by the ring while the latter is hanging upon and being turned by the shaft, means limiting the downward movement of said device, and two shoulders, one on the ring and one on the device adapted to come into engagement when said device is in its lowest position and when the ring has been raised out of contact with the shaft.

10. In trigger actuated power relay mechanism, the combination of a rotatable shaft, an eccentric ring embracing said shaft loosely, a shoe arranged below said ring and adapted to be raised and lowered and when raised to lift the ring out of engagement with the shaft and when lowered to allow

the ring to hang upon the shaft, means for holding said shoe in its lowered position, said means being arranged so as to be disengaged and rendered inoperative for that purpose by the action of the ring while the latter is being turned by the shaft, means for automatically raising said shoe when said upholding means are so rendered inoperative, and a device arranged above the

ring and adapted to be engaged and moved upward thereby while the ring is rotating.

In testimony whereof, I hereunto affix my signature in the presence of two witnesses.

DAVID PETRI-PALMEDO.
